[57] ABSTRACT

The tendency towards instability of a centrifugal compressor with a rotor with fixed bent-forward vanes is decreased in providing in this rotor jet channels for supply of liquid which on rotation form liquid vanes.

The direction of outflow of the jet openings are perpendicular to the axial direction of the rotor and the angle of outflow in respect to the radial direction are equal to the angle of the section of the fixed bent-forward vanes that is situated at the same diameter in the same plane of revolution.

FIG. 1

FIG. 2

FIG. 3

CENTRIFUGAL COMPRESSOR

BACKGROUND OF THE INVENTION

The invention relates to a centrifugal compressor of the type provided with a driven rotor with fixed vanes, which are bent forward towards the periphery of the rotor and in its direction of rotation.

Such a centrifugal compressor is known in the art.

Over a centrifugal compressor with a rotor provided with radial vanes it has the advantage that at equal circumferential velocity of the rotor the energy transferred per unity of weight of gas is higher. This advantage manifests itself in a reduction of the speed or in a diminution of the rotor-diameter for a centrifugal compressor, which has to yield a desired pressure ratio.

This advantage is faced by the disadvantage of an unfavorable adjustment behavior. For the energy transferred is far more dependent on the volumetric flow of gas and namely such that a decrease in this volumetric flow of gas at constant speed causes a decrease in the energy transferred by the rotor per unit of weight of gas. The reduction in the pressure ratios attended with it, in general gives a still further reduction in the volumetric flow of gas, causing a strong tendency towards instability to arise. This form of instability is indicated by the term of "surge" in Anglo-Saxon literature.

The object of the present invention is to improve the adjustment behavior of the above centrifugal compressor by highly decreasing the tendency towards instability.

THE INVENTION

The invention is characterized in that jets have been provided for the formation of fluid vanes in the rotor which jets on the one hand connect to a common central chamber linked up to an axial fluid supply and on the other hand end in jet openings provided in a substantially rotationally-symmetrical manner. The direction of outflow of these jet openings are substantially perpendicular to the axial direction of the rotor and the angle of outflow respecting the radial direction being substantially equal to the angle of the section of the fixed bent-forward vanes that is situated at the same diameter in the same plane of revolution, and in that the rotor in the way known in the art is enclosed by a compression chamber for fluid vanes that is in open connection with a fluid reservoir with which the fluid supply to the jets is connected and from which reservoir the compressed gas can be discharged via an outlet.

The fluid vanes that at high speed emerge from the rotor contribute considerably towards the transfer of energy to the gas to be compressed.

At a constant speed the mass-flow of fluid, contrary to the mass-flow of gas, is slightly affected by the gaseous pressure in the compressor-outlet. Therefore, at a certain position of the control valve in the fluid supply duct, a reduction of the mass-flow of gas will result in an increase in the mass-flow ratio between fluid and gas.

This causes an increase in the power that per unit of weight of gas is transferred to the gas via the fluid vanes. This increase compensates the decrease in the power transferred to the gas via the fixed vanes and a decrease in the pressure ratio that causes instability is avoided.

The jets may have been provided in the rotor independent of the fixed bent-forward vanes.

Advantageously the jet openings are provided in the tips of the fixed vanes.

5 Then, numerically, the jets correspond to the fixed bent-forward vanes and are partially provided in the fixed vanes. They can also be provided completely in the fixed vanes, thus in the center communicating with an annular common chamber in the way known in the art.

10 A further advantage is that the jets are completely provided in the fixed vanes.

DESCRIPTION OF THE DRAWING

15 The invention will be further described with reference to the drawings showing by way of example an embodiment of the invention, wherein

FIG. 1 a vertical cross-section through a centrifugal compressor, which is schematically shown;

20 FIG. 2 a section on an enlarged scale along line II-II of the rotor of FIG. 3;

FIG. 3 a side-view on an enlarged scale of a part of the rotor.

The centrifugal compressor shown in FIG. 1 consists 25 of a compressor housing 1, which is assembled with a fluid reservoir 2. A rotor 3 is centrally mounted in compressor housing 1 the rotor being which is fixedly connected to a shaft 4, with the bearing housing 5 thereof fixedly connected to housing 1.

30 Rotor 3 is driven by an electromotor 6 via shaft 4.

Rotor 3 is provided with fixed vanes 7 that are bent forward at the gas inlet side in the direction of rotation (see arrow in FIG. 3) and in respect of the axial direction, and that serve for the compression of gas, for example a freon gas, which is sucked by a suction nozzle 8.

35 Further, rotor 3 is provided with rotationally-symmetrical mounted jets 9 abutting a central chamber 10, chamber 10 is connected to a fluid supply duct 11 which, via an adjustment device 12, is connected to fluid reservoir 2.

40 The supply of fluid is effected as a result of the difference in gaseous pressure between the compressor-inlet and the compressor-outlet.

45 The chamber in which the fluid vanes are formed, is bounded by walls 13 and 14 of compressor housing 1.

50 In a manner known in the art the compressed gas is separated from the fluid in fluid reservoir 2 with the aid of partitions 15 and then discharged via outlet 16.

55 From the cross-section of a part of rotor 3 shown in FIG. 2, it can be clearly seen that via fluid supply 11 the fluid can enter into central chamber 10 and is further distributed over jets 9.

60 Jet openings 17 are provided in the tips of fixed vanes 7, which are clearly illustrated in the side-view of a part of rotor 3 shown in FIG. 3 on an enlarged scale.

65 Obviously, variations are made possible within the scope of the invention. For example, in the event of a large number of fixed bent-forward vanes, these vanes may be alternately provided with a jet. The jet openings can also lie in a surface of revolution different from that of the tips of the vanes, provided the jet openings are situated such that the fluid jets emerging from them are moving in a plane that is radial in respect of the rotor-shaft.

I claim:

1. A centrifugal compressor, comprising:
 a compression chamber having a central inlet for a
 gas;
 a driven impeller disposed generally in the center of
 said compression chamber;
 said impeller comprising a rotor provided with fixed
 vanes which are bent forward towards the peripher-
 ery of the rotor in its direction of rotation;
 means for rotating said impeller;
 said rotor being provided with jet channels extending
 therethrough for the passage of a fluid, the inlet
 ends of said jet channels being connected to a cen-
 tral fluid chamber and the outlet ends being pro-
 vided in a substantially rotationally-symmetrical
 manner, the direction of outflow of said outlet ends
 being substantially perpendicular to the axial di-
 rection of said rotor, and the angle of outflow in re-
 spect of the radial direction being substantially
 equal to the angle of the section of the fixed bent-
 forward vanes that is situated at the same diameter

5

in the same plane of revolution;
 said compression chamber having a pair of spaced
 parallel walls disposed on opposite sides of said im-
 peller and extending radially outwardly away from
 said impeller and terminating in an annular fluid
 collecting chamber, said parallel walls forming a
 compression chamber for fluid vanes effecting a
 compressive action upon a gaseous medium there-
 between; and
 a fluid reservoir in open connection with said com-
 pression chamber and having a discharge pipe for
 the compressed gaseous medium.

2. A centrifugal compressor according to claim 1,
 wherein the outlet ends of the jet channels are provided
 in the tips of the fixed bent-forward vanes.

3. A centrifugal compressor according to claim 2,
 wherein the jet channels are completely provided in the
 fixed bent-forward vanes.
